UNITED STATES PATENT OFFICE.

SIVERT MOE, EDWARD WATSON BUELL, GEORGE CRAY ROBERTS, AND ALLEN CONKLING, OF CHICAGO, ILLINOIS, ASSIGNEES TO THE TROY LAUNDRY MACHINERY COMPANY, LIMITED, OF TROY, NEW YORK.

STARCHING-MACHINE.

SPECIFICATION forming part of Letters Patent No. 611,015, dated September 20, 1898.

Application filed April 26, 1897. Serial No. 633,982. (No model.)

To all whom it may concern:

Be it known that we, SIVERT MOE, EDWARD WATSON BUELL, GEORGE CRAY ROBERTS, and ALLEN CONKLING, citizens of the United States, residing at Chicago, in the county of Cook, State of Illinois, have invented certain new and useful Improvements in Starching-Machines, of which the following is a specification, reference being had therein to the accompanying drawings.

This invention has relation to starching-machines for use in the process of laundering goods and articles of apparel; and it has in view, among other objects, the provision of a machine which is adapted to starch heavier articles of wearing-apparel, such as shirts and other articles, in contradistinction to lighter articles, such as collars and cuffs, and to apply the starch in the desired manner to those portions only of the article which require the starch, such as the wristbands and bosoms of shirts, while the remaining portions thereof are substantially protected from the operation of the machine.

A further object is to provide a machine in which all of its functions are under the control of a unitary device—that is, a single lever accessible to the operator.

The invention also comprises means for giving a yielding pressure to the goods in the process of starching the same, whereby variations in thickness are accommodated and the starch is forced into and through the goods or articles being operated upon.

A further purpose of the invention is to simultaneously prevent the baking of the starch to the walls of the starch receptacle or box, to heat the starch therein and to keep it heated, and to agitate said starch and keep it in thin condition, all of which is accomplished by the manner and means of applying steam under pressure to and within the starch-box.

Other objects and advantages of the invention will appear in the following description, and the novel features thereof will be particularly pointed out in the claims.

Referring to the drawings, Figure 1 is a substantially central vertical section of a starching-machine constructed in accordance

with our invention, certain parts being omitted. Fig. 2 is a left-hand elevation. Fig. 3 is a plan of the machine. Fig. 4 is a diagrammatic illustration of the belt-shifting sector on the curved line 4 4 of Fig. 2. Fig. 5 is a right-hand elevation showing the side opposite that illustrated in Fig. 2. Fig. 6 is a side elevation illustrating the position of the principal parts at the completion of the starching operation and while the stripping-rolls are acting to deliver the articles from the machine. Fig. 7 shows in side elevation the position assumed by the parts to permit the introduction of an article into the machine. Figs. 8 and 9 are detail illustrations of the spring-detent, hereinafter described, on the lines 8 8 and 9 9 of Fig. 6, respectively. Fig. 10 illustrates the lowest position of the controlling-lever, as hereinafter described. Fig. 11 is a partial front elevation. Fig. 12 is a plan of the starch-box with the top removed. Figs. 13, 14, and 15 are illustrations of modified forms of starch-pads and paddles which may be employed in the machine.

Like letters refer to like parts in all the figures of the drawings.

A represents a pedestal or column for the support of a starch box or receptacle A', which may be cast integral with the column, as shown, or formed separately therefrom and secured thereupon, as desired, and provided with a suitable outlet-cock A''. To prevent corrosion and consequent discoloration of the starch within the box A', there is provided a lining, of copper or other non-corrosive material, which closely fits the interior of the box and is extended over and about the edges thereof, as clearly shown at A² in Fig. 1. In the bottom of the box A' there is formed an opening into which is screw-threaded a steam-nozzle of peculiar construction, the edges of the lining at said opening being bound and protected by the flange B' of said nozzle B. Into the side wall of the nozzle B there is fitted a steam-supply pipe C, and in the bottom of the nozzle there is fitted a drain-pipe C' for the discharge of the water of condensation. These pipes pass through openings A⁴, formed in the column A. The nozzle B

is closed at its top by a screw-threaded cap B^2 , having upon its upper surfaces wrench-lugs B^3 for the grip of a suitable tool for inserting and removing said cap. The cap B^2 is formed with small perforations B^4 , preferably dispersed or disposed so as to direct small jets of steam into the starch and upon lines other than vertical. This means for the introduction of steam into the starch-box prevents the blowing of the starch upwardly through any opening out of the box. It also subdivides the steam into small jets distributed in various directions other than vertical, whereby the starch is agitated and prevented from adhering to the walls of the box. A further advantage in this regard is that the steam is so thoroughly diffused throughout the starch that it is not only kept heated, but is also maintained in a thin condition, which is very advantageous when the starch is being applied to and impressed into an article in that it is more readily taken up by the fabric of the article and absorbed into the fibers thereof, requiring less pressure of the paddles upon the goods and therefore less destructive wear thereon.

The starch-box is provided with a cover, one portion, D , of which is movable, and the other portion, D' , of which is fixed. Secured to the movable section D of the cover are two arms D^2 , to which is secured in any suitable manner a pad-base D^3 , preferably of sheet metal, or of cast metal suitably protected from corrosion, or of non-corrosive material. Secured to said base in any suitable manner are a pad D^4 , of felt or other absorbent material, and an exterior covering D^5 , of a suitable textile fabric of one or more thicknesses, the object being that the absorbent portion shall take in and hold and pay out under pressure starch, while the function of the covering D^5 is to permit the entrance and discharge of starch from the portion beneath it to any article being starched by the machine, but by reason of the finer texture of the covering causing the starch to be more or less finely divided when coming into contact with an article and in less quantity than were the pad employed without a covering.

Coöperating with the pad above described there is a paddle E , which preferably consists of a non-corrosive plate of substantially the same superficial area as said pad and mounted for a reciprocating motion to and from the pad. The paddle E may be perforated, as shown, so that after having been pressed against an article and pressing said article against the starch-pad, whereby the starch therein is forced from the pad and through the article, the paddle in being withdrawn from the article will not by suction remove so much of the starch from the article as it would if the surface of the paddle were perfectly plain. It is evident, however, that such a plain paddle may be employed.

In Figs. 13, 14, and 15 are represented modifications of the pad and of the paddle which

may be employed. In Fig. 13 the absorbent body of the pad D^4 is represented as perforated to form pockets d^{4x} , while the paddle E is plain, and in Fig. 14 the absorbent portion of the pad is represented as provided upon its face with corrugations D^{4x} and in this instance with no covering D^5 thereon. In Fig. 15 the paddle E is formed with a corrugated and perforated face E'^x of sheet metal, the perforations communicating with air-spaces within the corrugations, whereby whatever advantages may exist in a paddle having perforations to admit ready passage of starch through an article will be present in the paddle, while the open or free ends of the corrugations will prevent suction upon the part of the paddle which would draw the starch from the article upon the backward movement of a paddle therefrom. The paddle E is secured to a rock-arm E' , which in this instance is bifurcated, as shown, to give a broader bearing on the paddle. The rock-arm is bifurcated at its opposite end and pivotally supported, as at E^2 , at opposite points on the column A . Between its points of support and its paddle end the rock-arm is curved so as to pass upwardly along the starch-box and over and into the same, and at about its mid-length there is connected to the arm by means of a pivot E^3 an adjustable lever E^4 , carrying an antifriction-roller E^5 at one end and connected with the lever E' at the opposite end by means of a bolt E^6 , encircled by a spring E^7 , seated upon or in a socket E^8 in the lever E' . Between the pivot E^3 and the bolt E^6 is an adjusting-bolt E^9 , screw-threaded through the lever E^4 and bearing against the lever E' and carrying a set-nut E^{10} . This bolt E^9 adjusts the distance between the pad and paddle for light or heavy goods and also the tension of the spring E^7 accordingly.

From the starch-box A' there project rearwardly two brackets A^5 , providing bearings for the power-shaft F of the machine, and on this shaft is fixed a cam F' , rotating in the plane of the roller E^5 . Now when power is applied the rotation of the cam F' , against which the antifriction-roller E^5 is constantly held by the light coiled spring E^{11} , connected to the lever E' and adjustably connected by a bolt E^{12} with a projection A^6 on the column A , a reciprocating motion is given to the paddle E practically in a horizontal plane agreeing with that of the starch-pad. Now by reason of the pivotal and adjusted yielding connection of the lever E^4 with the lever E' the pressure of the paddle is more or less yielding in accordance with the tension given to the spring E^7 and by the bolts E^6 and E^9 . In starting new material and heavier articles which are not new it requires a greater pressure to force the starch therethrough than when said articles are lighter or as heavy and have been frequently laundered.

Yielding pressure has heretofore been employed in the art, but in such a manner that when the spring employed to adapt a paddle

to varying thicknesses of goods was once compressed the expansion of said spring would cause a jarring or other movement of the paddle during its movement away from the pad and the article thereon. By the construction hereinbefore described a yielding pressure of the paddle is secured and at the same time the movement thereof and of the parts directly related thereto is exceedingly smooth and free from concussion or jarring. This adds materially to the character of the work accomplished by the machine and to the life of the machine itself. This will be apparent when the arm E' is considered as a rigid member of mechanism giving motion to the paddle E, the cam F' being also a rigid member, while the lever E⁴ is an interposed yielding member of such mechanism. It is the interposition of a yielding member under adjusted tension at an intermediate point upon a rigid member and the application of power substantially at such point which gives the desired yielding pressure at the paddle and smoothness of motion in and of all the parts concerned.

The arm E' passes through a hood D'^x, formed in the section D' of the cover of the starch-box. By reference to Fig. 3 it will be noted that the section D' of the cover is also formed with a hood D^{2x} and the section D with a hood D^x, each adapted to substantially cover a stripping-roll G' G, respectively, and that each section of the cover is provided with buttonhole-slots d and screws or bolts d' for retaining the cover-sections upon the box. At the rear edge of the section D' the slots d^x are open-ended to receive the bolts d'^x. At the ends of the cover-sections they overlap, as shown at d², Fig. 2. In the section D the slots d are sufficiently long to permit of a reciprocation of said cover-section, as hereinafter described, and both sections may be removed by simply moving them until each screw or bolt d' rests in the eye of the buttonhole-slot, when the section may be lifted from the box. The section D' of the cover is also provided with housings D^{3x} for the movable bearings of the roll G', there being one at each end of the cover. By reference to Fig. 6 it will be seen that the stripping-roll G' is mounted at each end in an eyebolt g, passing through the vertical walls of the housing D^{3x}, and is encircled by a coil-spring g' and an adjustable collar g², which in use is arranged a slight distance from the adjacent wall of the housing when the two rolls G' G' are in contact with each other, thus giving a yielding pressure and maintaining contact of said rolls after a slight separation of the cover-sections, as and for a purpose hereinafter described.

The bearings for the roll G are fixed to or made a part of the section D, as shown at d³, whereby said roller is carried by and moved with said cover-section. At the right end of the roll G' there is secured a gear-wheel G², which when rotated by means hereinafter

described rotates both of the stripping-rolls when in contact with each other for the purpose of removing any surplus starch in an article as it is carried out of the machine by said rolls.

There have been thus far described the essential elements of a starching-machine and incidentally some of their novel adjuncts. Taking as essentials any starch-box, paddles, and stripping-rolls, it remains to describe means for the control of the operation of these devices by a single lever. The means for accomplishing this object by the use of a single hand of the operator, leaving the other hand free to handle the article being starched, will now be described.

Upon the shaft F are mounted a fast and a loose pulley F² F³, respectively, and a reciprocating belt-loop F⁴, mounted on a sleeve F⁵, in a lug F⁶ of which the head of a belt-shifting lever H operates loosely. The loop F⁴ is held by a set-screw f in the end f' of an arm f², projecting from the sleeve F⁵, as clearly shown in Fig. 2. The lever H is pivoted at H' to a wall of the starch-box and is extended beyond its pivot and provided with a pin H², so that the said lever may be vibrated on its pivot to throw the belt from one to the other of the pulleys F² F³ for starting and stopping the machine. Upon the opposite end of the shaft F is a sprocket-wheel I, secured thereto rigidly by a set-screw I'. A bifurcated yoke J is by its location upon the shaft F pivotally supported thereby. The bifurcations J' of this yoke embrace the sprocket-wheel I and its hub and by this means is prevented from longitudinal movement upon the shaft. A yoke might be supported upon the shaft by a single bearing thereon; but by employing the bifurcated bearing J' J' a broader surface contact is secured, so as to maintain the yoke and its adjuncts in a uniform plane during its oscillations on its bearing. The purpose of the yoke J is to convey power from the shaft F to the stripping-rolls and to provide means for controlling the use of said power in the matter of the time and duration thereof. A companion sprocket-wheel I² is mounted in bearings J², formed in the yoke J, and is operatively connected with a gear G^{2x}, which is adapted to mesh with the gear G² of the stripping-roll G' when the yoke is elevated at its free end. A sprocket-chain I³ connects the sprockets I and I².

At each end of the cover-section D there is formed or secured a depending bracket K, having upon its inner surface a track K', formed by ribs K². By these tracks or grooves, which are widened at their lower ends, as shown, the sliding section D of the cover may be opened and closed by suitable means, while the widened portion of the track permits an inoperative movement of the devices employed for a limited portion of the movement thereof for a purpose hereinafter described.

Thus far there have been described the es-

5 essential elements of a starching-machine—to wit, the box, the paddle, and the stripping-rolls—and in addition the essential means for operating the same—to wit, a power-shaft, 10 primarily operating the paddle, a belt-shifter, and sprocket-gearing for conveying to and controlling the use of the power necessary for the operation of the stripping-rollers. It 15 now remains to provide mechanism for controlling the operation of the several moving parts.

15 It will be observed that both the yoke and the belt-shifting lever are projected toward the front of the machine. Along said front there is arranged a shaft L, (see Fig. 2,) which is mounted in brackets L', Fig. 11, one at each end of the box. At the right hand of the machine there is mounted upon the shaft L a lever M, by means of which all of 20 the functions of the machine are controlled. The lever M projects from a collar M', rigidly mounted on the shaft L. This collar is formed or provided with various arms and projections for coöperation with the yoke J and the 25 cover-section D through the medium of the bracket K. A rock-arm M², carrying a pin M³, serves to open and close the cover-section D by the travel of the pin M³ in the track K', formed by the ribs on the bracket K. In 30 line with the arm M² is a projection M⁴, which is in the plane of a spring-latch j, which is secured to the yoke J by a screw or bolt j', passing through a slot j² therein and entering the yoke. The latch is pressed by a spring 35 j⁴, which surrounds a post j⁵ and bears on a cross-piece j⁶ toward the end of the yoke, but is capable of moving in a direction from said end. The projection M⁴ and a portion of the latch with which it coöperates are in a plane 40 different from that occupied by the yoke. The end of the yoke rests normally upon the sleeve M', as clearly shown in Fig. 11. The inner end of the sleeve consists of a disk M⁵ (see Fig. 10) with a portion removed, so that 45 the remaining edges may abut against a stop M⁶, projecting from the wall of the starch-box at the two extremes of the movements of the lever M.

50 Upon the inner face of the disk M⁵ (see Figs. 8 and 9) there are recesses M⁷ and M⁸, having walls inclined at different angles, into which a spring-pressed detent M⁹, provided with a handle M¹⁰, Fig. 11, mounted in the bracket L', automatically seats itself to temporarily retain the lever M with different degrees of resistance in certain positions assumed in its use for the purpose of controlling the work of the machine. The position 55 assumed by the detent in Fig. 8 is at a time when the lever M is in the position which it assumes when the cover is open, as clearly shown in Fig. 7, and when the detent is occupying the depression M⁸ of the disk the lever is vertical and the cover is closed and the 60 yoke raised to give rotation to the stripping-rolls. The stop M⁶ is utilized with the disk 65 when the cover is open, as shown in Fig. 10,

and when the cover is closed, the paddle in operation, and the lever M inclined away from the operator, as shown in Fig. 5. It 70 will thus be seen that the lever M and the devices connected therewith at the right of the machine serve to control the opening and closing of the cover and the rotation of the stripping-rolls. When the detent rests in the 75 round seat M⁸, Fig. 6, the lever will be indicated to be in a proper vertical position and the walls of the recess will afford a resistance against the movement of the lever in either direction. When the detent is in seat M⁷, Fig. 7, it indicates that the rolls are open for the introduction of the article; but if it is desired to remove the cover the detent may be forced from said seat and the disk further rotated. These seats thus indicate when the 80 lever and its adjuncts have reached the proper position for the different operations and also assist in retaining the lever in such position.

85 By reference to Figs. 2 and 4 the devices 90 mounted on the left end of shaft L will be clearly understood. These devices comprise means for opening and closing the movable cover-section or assisting in such function and for vibrating the belt-shifting lever II, 95 the functions of the last-mentioned devices being properly timed with relation to the devices located at the right end of the shaft and heretofore described. A collar N is mounted upon the shaft L and carries a rock-arm N', with a pin N², which travels in the path or track K' of the bracket K, made on or secured to and depending from the movable cover-section D. This rock-arm and bracket are the duplicates of the similar devices already described in connection with the right end of the machine, and while not absolutely essential they contribute to a more direct application of power to the movable cover-section, and thus insure smoothness 100 and ease of action. The collar N is also provided with or secured to a sector O, which has a curved groove or path on its periphery. The contour of this path comprises two straight portions O' and O², slightly out of 105 line with each other, and a diagonal portion O³, connecting the two straight portions. (See Fig. 4.) The circles in Fig. 4 represent the various positions assumed by the pin II² of the belt-shifting lever II in the groove or 110 path formed in the periphery of the sector O. When the pin is at the point 1, the machine is idle and the cover-section D and rolls are open, as shown in Fig. 7, and the machine is in a condition to receive an article 115 to be starched. After the article has been properly introduced the lever M is brought from the forwardly-inclined position to the rearwardly-inclined position. (Shown, respectively, in Figs. 7 and 5.) In this movement of the lever the pin II² occupies the positions 1, 2, and 3, Fig. 4, and in passing from position 2 to position 3 the lever II is 120 oscillated on its pivot and the belt shifted 125 to the rearwardly-inclined position. (Shown, respectively, in Figs. 5 and 7.) In this movement of the lever the pin II² occupies the positions 3, 2, and 1, Fig. 4, and in passing from position 3 to position 2 the lever II is 130 oscillated on its pivot and the belt shifted to the forwardly-inclined position. (Shown, respectively, in Figs. 7 and 5.)

from the loose pulley F^3 to the tight pulley F^2 , whereby power is applied and the paddle E set to work. In the meanwhile the arms N' and M^2 have served to close the cover and bring the rolls G and G' together, fully accomplishing these functions when the pin has reached position 2 and before the belt is shifted and therefore before the paddle is set to work. Now taking the sector O , with the pin at position 3 and with the paddle doing its work, it is desired to perform the operation of stripping. The lever M is now brought from the rearwardly-inclined position to a vertical position. (See Fig. 6.) In this movement the pin is changed from position 3 to position 4, thus not changing the position of the belt-shifting lever; but the devices on the right end of the shaft have coaxed to move cover-section D and the starch-pad away from paddle E and to place the gear G^{2x} in mesh with the gear G^2 , and the belt not having been shifted gives power to the sprocket wheels and chain, and the stripping-rolls are rotated in such a direction as to eject the article from the starch-box and to press the surplus starch therefrom, when by a further movement of the lever M the sector O is moved, so as to throw the pin from the position 4 to a position near to and the equivalent of the position 2, thus moving the lever H on its pivot and shifting the belt to a loose pulley F^3 and stopping the machine. This movement of the lever M has not separated the rolls. They are still closed, have ceased rotation, and retain whatever starch is left adhering thereto below their line of contact. This is important to prevent not only the escape of starch, but the presence of an undue quantity thereof on the rolls, where it will be liable to be smeared upon undesired portions of an article subsequently introduced into the machine. A further movement of the lever brings the pin and sector in the relative position shown at position 1.

While the movement of the lever has produced the different relative positions of the sector O and pin H^2 at one end of the shaft, as above described, the devices at the other end of said shaft have performed their described functions and all in their proper time and order. It is to be noted that the pin M^3 of arm M^2 , as well as its associate pin N^2 of arm N' at the other end of the shaft, occupies the contracted portions of the tracks K' in the brackets K at such times, as by means of the said pins movements of the movable cover-section D occur. The said pins occupy the widened portion of said tracks when the lever M is moved to produce the other effects accomplished—to wit, holding the stripping-rolls closely together during the beating of the paddle by contact with the curved wall K^2 , Fig. 2, and when the lever M is depressed below the position shown in Fig. 7 for the purpose of entirely removing cover-section D by hand. In the latter function, and even

in the function of closing the cover and bringing the rolls together, the latch J recedes under the action of projection M^4 , so that the gears shall not be brought into mesh by the forward movement of the lever M .

When the lever M is brought from its most rearward position (shown in Fig. 5) to the vertical, (shown in Fig. 6,) the inoperative portion of the belt-shifter sector O has been employed from position 3 to position 4, Fig. 4, so that the belt remains on the tight pulley. During this movement of the lever the projection M^4 has been moved from the position shown in Fig. 5 to the position shown in Fig. 6, raising the yoke J and putting its gearing in mesh with the gear G^3 , which by the movement of the cover-section D and the expansion of the springs g' has moved toward the front of the machine the same distance that the cover-section has been moved. The movement of the latter carries with it the starch-pad D^4 beyond any compressing action thereon or against an article thereon by the still vibrating paddle E . In this manner the paddle does not interfere with the ejection of an article by the stripping-rolls. These rolls, it is understood, are preferably of or covered with rubber. From the above description it will be seen that all of the various principal elements of the machine are compactly arranged and are brought under control by comparatively non-intricate construction through the action of a single device—to wit, the controlling-lever M .

The operation of the machine is as follows: Taking the parts in the position shown in Fig. 7, the machine is ready for the introduction of an article, which is placed within the starch-box in front of and naturally hanging against the starching-pad. One simple straightforward movement of the lever M first grips the article between the stripping-rolls with only such portions as are to be starched within the machine and advances the pad into operative position with relation to the paddle. A successive movement of the lever in the same direction then shifts the belt onto the tight pulley, and the paddle E at once begins pressing against the article and forcing the starch out of the saturated pad into and through the article and withdrawing a minimum quantity in its backward movement therefrom. Now it only requires a simple return movement to a vertical position of the lever M to stop the starching function and to accomplish the stripping and ejecting functions of the machine, when a further simple movement of the lever separates the cover-sections, the stripping-rolls, and the paddle and pad for a reception of a subsequent article.

The simplicity of the movements of the unitary controlling device or lever is at once apparent as being entirely devoid of any possible misunderstanding, so that the work of the operative is by necessity simplified, and by the positive control of the machine secured through the medium of this single de-

vice the various functions are performed without the direct application of force by the hand of the operator to and upon the specific devices which perform said functions. The 5 progressive movements of the unitary controlling-lever bring about the successive performance of the various functions—to wit, starting, starching, opening for the removal of the goods, and stopping—without the application of the hand to the mechanism which 10 performs these functions.

It is apparent that the details of the connecting device between the controlling-lever and the power, starching, and stripping mechanisms may be varied in numerous particulars of construction and arrangement, and yet 15 serve the purpose of their use. The invention is therefore not limited in this regard, but may be altered in construction and arrangement to any degree within the scope of 20 mechanical skill without a departure from the scope thereof.

What we claim is—

1. In an organized starching-machine, 25 starching mechanism, stripping mechanism and stripping-roll-shifting mechanism and a single device operatively connected with said mechanisms for controlling their successive operation.

2. In an organized starching-machine, belt-shifting mechanism, starching mechanism, separable stripping mechanism, and a unitary device for controlling the successive operations of said mechanisms.

3. In an organized starching-machine, the combination of starching mechanism and separable stripping mechanism, and a unitary means for bringing together and separating the stripping mechanism and for operating 40 and separating the starching mechanism and for properly timing said operations.

4. In a starching-machine, starching mechanism, stripping mechanism, stripping-roll-separating mechanism, means for operating 45 each of said mechanisms, and a single, unitary controlling-lever and suitable connections by which said mechanisms are brought into action in their proper order, substantially as specified.

5. In an organized starching-machine, belt-shifting mechanism, starching mechanism, positively-rotating stripping mechanism, and a movable cover-section, and a single lever and suitable connections for both controlling 55 said mechanisms and for opening and closing said cover-section.

6. In a starching-machine having a cover, starching mechanism and positively-rotating stripping mechanism, a member of each of 60 which is mounted to move with a section of the cover of the machine, and unitary means for operating said mechanisms and controlling the movements of said cover-section.

7. In a starching-machine, starching mechanism, stripping mechanism and belt-shifting mechanism, and a unitary device and connec-

tions for gripping the work by the stripping mechanism, shifting the belt to operate the starching mechanism, separating the members of the starching mechanism to render it 70 practically inoperative, rotating the stripping mechanism and separating the same whereby the machine is adapted to subsequently operate upon another article.

8. In a starching-machine, a power-shaft 75 provided with belt-shifting mechanism, a starching-mechanism member operatively connected with said shaft and with power-conveying devices thereon, a sliding cover-section carrying an opposite member of the 80 starching mechanism, and a lever operatively connected with means for successively operating and controlling the cover-section and the belt-shifting mechanism.

9. In a starching-machine, starching mechanism having a movable member and stripping mechanism comprising shiftable members, and a unitary device and connections for separating the members of the starching mechanism and simultaneously moving and 90 retaining the stripping members together; substantially as specified.

10. In a starching-machine, starching mechanism and separable and rotatable stripping mechanism, and a unitary device and connections for stopping the rotation of and subsequently separating said stripping mechanism.

11. In a starching-machine, shiftable separable stripping mechanism, means for intermittently rotating the same, and means for shifting the same, both means being controlled 100 through the medium of one and the same device.

12. In a starching-machine provided with shiftable stripping mechanism, starching 105 mechanism, a power-shaft and power-conveying devices, a controlling-lever connected with mechanism for rendering the stripping mechanism operative in a different plane thereby simultaneously rendering the starching mechanism inoperative while the power-shaft is rotating.

13. In a starching-machine, a belt-shifting-lever-controlling device having operative and non-operative portions, means for connecting 115 the said device with a controlling-lever operatively connected with means for rendering the stripping mechanism of the machine operative while the belt-shifting portion of said device is non-operative.

14. In a starching-machine, a belt-shifting-lever-controlling device having operative and non-operative portions, and means for connecting the said device with a controlling-lever provided with means for operating a movable cover while an inoperative portion of the belt-shifting device is in use.

15. In a starching-machine, a movable starching-paddle, a power-shaft and a lever carrying the paddle, and an interposed lever 130 pivotally and yieldingly connected with the paddle-lever.

16. In a starching-machine, a movable starching-paddle, a power-shaft and a lever carrying the paddle, an interposed lever pivotally and yieldingly connected with the paddle-lever, and means for adjusting said yielding connection. 5
17. In a starching-machine, means for introducing steam therein at a substantially central point in the form of jets dispersed upwardly in various directions. 10
18. In a starching-machine, a steam-supply pipe communicating with an exterior chamber having communication with a starch-box at a substantially central point therein by means of dispersed jet-openings diverging upwardly from said central point. 15
19. In a starching-machine, stripping-rolls provided with means for rotating one of said rolls, a yoke having a latch and carrying gearing extending from and mounted at one end upon the power-shaft to a point adjacent to the stripping-rolls, and a lever constructed and arranged to move the yoke and its gearing toward the stripping-rolls, substantially 25 as specified.
20. In a starching-machine, a sliding cover-section carrying one of a pair of stripping-rolls, a fixed cover-section provided with yielding bearings for the other stripping-rolls of the pair, a yoke carrying gearing for rotating one of said rolls, a lever and connecting devices for lifting the yoke to bring its gearing into mesh with gearing upon the stripping-roll during the movement of the lever in one direction, and a device for preventing this operation by movement of the lever in the opposite direction, substantially as specified. 30
21. In a starching-machine, a movable cover-section provided with a track having a widened and a contracted portion, in combination with a lever operatively connected with a rock-arm projecting into said track and with devices for coöoperating with other elements of the machine whereby said rock-arm is inoperative upon the cover-section when in the widened portion of the track, substantially as specified. 40
22. In a starching-machine, the combination with a fixed cover-section carrying a stripping-roll in yielding bearings, a movable cover-section carrying a stripping-roll and a starching-pad, a reciprocating starching-paddle, and mechanism comprising a unitary lever and connections for moving the cover-section and pad in a direction from the paddle and for rotating the stripping-rolls, substantially as specified. 50
23. A starching-machine comprising an integral column and starch-receptacle having a screw-threaded aperture, a lining seated in said aperture, and a flanged, screw-threaded steam-chamber threaded into the aperture, substantially as specified. 60
24. In a starching-machine, a steam-supply pipe communicating with the interior of the starch-box by a connection the opening of which is closed by a perforated plug, the perforations being divergent from its center substantially as specified. 65
25. In a starching-machine, a chamber or steam connection adapted to receive a steam-supply pipe and provided at its bottom with a drain-pipe and at its top with a cap or closure having perforations inclined with relation to the vertical axis of the chamber, substantially as specified. 70
26. In a starching-machine and in combination with the power-shaft thereof, a pivoted paddle-lever carrying a pivoted lever adapted to contact with a cam on the power-shaft at one side of its pivot and connected at its other end with the paddle-lever through the medium of a spring-encircled bolt, and adjusting devices arranged between the said bolt and the pivot of the lever, substantially as specified. 80
27. In a starching-machine, a movable cover-section secured in position by button-hole slots and bolts, in combination with a controlling-lever operatively connected with said cover-section, the slots being proportioned in length to retain the cover in position during its movements when the machine is in use and to permit of the removal of the cover by an extended movement of the lever, substantially as specified. 85
28. In a starching-machine, the combination of a movable cover-section provided with brackets having tracks and carrying a stripping-roll, with a fixed cover-section carrying a stripping-roll, and with a controlling-lever provided with means operating in said tracks for closing and locking in a closed position the movable cover-section, substantially as specified. 90
29. In a starching-machine, the combination with a belt-shifting lever, of a sector operatively connected therewith and having non-operative portions slightly out of line with each other and an intermediate operative portion, a rock-arm, a movable cover-section, and means for operating the sector and rock-arm, substantially as specified. 95
30. In a starching-machine comprising belt-shifting, starching and stripping mechanisms, the latter including separable members, the combination with said mechanisms of a single unitary controlling-lever and suitable connecting devices by which the successive movements of said lever control the complete and successive functions of said mechanisms in their proper order, substantially as specified. 105
31. In a starching-machine, starching mechanism, stripping mechanism, tank-closing mechanism, means for successively operating each of said mechanisms, and a single unitary controlling-lever and suitable connections by which said successive operating means are brought into action in their proper order, substantially as specified. 110
32. In a starching-machine, comprising belt-shifting, starching, and stripping mechanisms, the combination with said mechanisms 120
- 65

- of a single unitary controlling-lever and suitable connecting devices constructed and arranged to cause an article to be clamped and the commencement of the starching operation 5 when said lever is at one extreme of its movement, and to cause the remaining functions of the machine to be performed in regular successive movements of said lever in one direction whereby contrary and diverse movements 10 of the controlling-lever are obviated and the work of the operative is materially simplified.
33. In a starching-machine, the combination with the movable cover-section D, of the brackets K having the tracks K', the lever M, the shaft L, and the rock-arms M² and N', substantially as specified. 15
34. The combination of the yieldingly-mounted stripping-roll G', the roll G, the cover-section D having brackets K, the shaft 20 L carrying the lever M, the rock-arms, and the sector having a non-operative portion, substantially as specified.
35. The combination of the movable cover-section carrying a pad and a stripping-roll, a 25 coöperating vibrating paddle, the fixed cover-section carrying a yieldingly-mounted stripping-roll, the yoke J, the lever M, the shaft L, and the collar M' having a projection M⁴, substantially as specified.
36. In a starching-machine, a starching-receptacle having an aperture for the reception 30 of a steam connection, a lining for the receptacle seated in the aperture, a chamber or steam connection provided with a flange to retain said lining in position, a perforated plug at the upper portion of said chamber, a steam-supply pipe communicating with said chamber, and a drain-pipe at the lower portion of said chamber, substantially as specified. 35
37. In a starching-machine, a standard or column, a pivoted paddle-lever supported on said standard, a power-shaft provided with a cam, a lever pivoted to said paddle-lever, a bolt extending from said pivoted lever through the paddle-lever, and a spring surrounding said bolt, substantially as specified. 40
38. In a starching-machine, a standard or column, a pivoted paddle-lever supported on 45 said standard, a power-shaft provided with a cam, a lever pivoted to said paddle-lever, a bolt extending from said pivoted lever through the paddle-lever, a spring surrounding said bolt, and a set-screw passing through said pivoted lever and bearing against the paddle-lever, substantially as specified.
39. In a starching-machine, a standard or 50 column, a pivoted paddle-lever supported on said standard, a power-shaft provided with a cam, a lever pivoted to said paddle-lever, a bolt extending through the paddle-lever from said pivoted lever, a spring surrounding said bolt, and a tension-spring extending from said paddle-lever to a support upon the standard, substantially as specified. 55

40. In a starching-machine, a pad, a power-shaft provided with a cam, a supporting-standard, a paddle-lever pivoted thereto and extending at an angle from its pivotal point, a yielding contact for said cam carried by said paddle-lever, and a spring connected to said lever and standard to exert a retractive tension on the lever, substantially as specified. 70

41. In a starching-machine, the combination with a stripping-roll yieldingly mounted 75 in a cover-section and provided with a gear-wheel, of a pivoted yoke provided with a latch and with a gear-wheel to mesh with the gear upon the stripping-roll, power-transmitting means carried by said yoke, and pivoted means for lifting said yoke to bring said gear into mesh, substantially as specified.

42. In a starching-machine, the combination with a stripping-roll yieldingly mounted 80 in a cover-section and provided with a gear-wheel, of a pivoted yoke provided with a gear-wheel to mesh with the gear upon the stripping-roll, power-transmitting means carried by said yoke, pivoted means for lifting said yoke to bring said gear into mesh, and a spring-actuated latch to engage said lifting means, substantially as specified. 85

43. In a starching-machine, the combination with a stripping-roll yieldingly mounted 90 in a cover-section and provided with a gear-wheel, of a pivoted yoke provided with a gear-wheel to mesh with the gear upon the stripping-roll, power-transmitting means carried by said yoke, pivoted means for lifting said yoke to bring said gear into mesh, and a spring-latch provided with an inclined surface to permit the lifting means to move said latch in its movement in one direction, substantially as specified. 95

44. In a starching-machine, the combination with a stripping-roll provided with a driving-gear, of a yoke having a latch and carrying a meshing gear and provided at one end with a bifurcated portion, a power-shaft on which said bifurcated portion is journaled, a sprocket-wheel secured to said power-shaft between the arms of the bifurcated portion, a sprocket-wheel carried by said yoke, a sprocket-chain extending between said sprocket-wheels and a pivoted lever located 110 at the free end of the yoke, substantially as specified. 105

45. In a starching-machine, the combination with a shiftable stripping-roll provided 115 with a driving-gear and with means for shifting said stripping-roll, of a yoke carrying a latch and a meshing gear and adjustable to and from the gear on the stripping-roll, a power-shaft on which the yoke is pivoted, a sprocket-wheel carried by said yoke, a sprocket-wheel secured upon said power-shaft, and a chain extending between said sprocket-wheels, substantially as specified. 120

46. In a starching-machine, the combination with a shiftable stripping-roll carrying a 125

5 gear, of a pivoted yoke provided with a latch and a meshing gear, means communicating with a driving-shaft to drive said gears, means for shifting said stripping-roll and a lever having a projection to engage said latch and move said yoke, substantially as specified.

47. In a starching-machine, the combination with a stripping-roll carrying a gear, of a pivoted yoke provided with a meshing gear, means communicating with a driving-shaft to drive said gears, a rotating collar carrying a projection to engage and move said yoke, and an extension from said yoke resting upon said collar to limit the movement of the yoke 15 away from the stripping-roll, substantially as specified.

48. In a starching-machine, the combination with a stripping-roll carrying a gear, of a pivoted yoke provided with a latch and a 20 meshing gear, means communicating with a driving-shaft to drive said gears, a rotating collar carrying a lifting projection to engage and move said yoke, and an extension from 25 said yoke in a different vertical plane from said lifting projection and latch and resting upon said collar, substantially as specified.

49. In a starching-machine, a rotating collar connected with a controlling-handle, a rock-arm carried by said collar and having 30 a pin extending therefrom, a lifting projection carried by said collar, and a disk carried by said collar whereby in the rotation of the collar the several parts carried thereon will perform their respective functions, substantially as specified.

50. In a starching-machine, the combination with cover-operating, belt-shifting, starching and stripping mechanisms, of a unitary controlling-lever mounted to rotate 40 a disk, and means to engage said disk to hold the same in its adjusted positions; substantially as specified.

51. In a starching-machine, a controlling-lever, a disk rotated thereby and provided 45 with depressions in one face thereof, and a spring-detent adapted to seat itself in said depressions, substantially as specified.

52. In a starching-machine, a controlling-lever, a disk rotated thereby and provided 50 with sockets having walls at different angles, and a spring-detent adapted to seat in said sockets and to offer varying degrees of resistance to the rotation of the disk and to indicate the progress of the lever, substantially as specified.

53. In a starching-machine, a controlling-lever, a disk rotated thereby and provided with sockets upon one face thereof, a bracket carried by said machine, and a spring-pressed 60 detent bearing against said disk, substantially as specified.

54. In a starching-machine, the combination with cover-operating, belt-shifting, starching and stripping mechanisms, of a unitary controlling-lever, means rotated thereby, and

a device carried by the machine contacting with the rotated means at successive points to determine the successive positions of the lever for accomplishing the several functions of the machine during the movements of said 70 lever; substantially as specified.

55. In a starching-machine, comprising a movable cover-section, stripping-rolls and belt-shifter a controlling-lever, means connected therewith and rotated thereby to move 75 the cover-section, shift the belt, and to place the stripping-rolls in gear with the rotating means during the movement of the lever, substantially as specified.

56. In a starching-machine, a controlling-lever, a sector rotated thereby, a path or way upon the periphery of said sector and having inoperative portions, a belt-shifting lever connected to the sector so that in the movement of the sector a portion of the track 85 or way will not act upon the belt-shifter, substantially as specified.

57. In a starching-machine, the combination with belt-shifting, starching and stripping mechanisms, of a unitary controlling-lever, a sector rotated by said lever and having a path portions of which are out of line 90 with each other, a pivoted belt-shifting lever, a projection from said belt-shifting lever operatively engaging a laterally-disposed portion of said path on said sector, and belt-shifting means at the opposite end of said belt-shifting lever; substantially as specified.

58. In a starching-machine, a power-shaft provided with fast and loose pulleys, a sliding collar carrying a belt-loop, a belt-shifting lever for moving said collar, a cam secured on said shaft, a paddle-lever reciprocated by said cam, a sprocket-wheel secured to said shaft, shiftable stripping-rolls and gear, and 105 means for transmitting the power from said sprocket-wheel to said stripping-rolls, substantially as specified.

59. In a starching-machine, a controlling-lever, a collar rotated by said lever and provided 110 with means for moving a cover-section and for throwing into gear a stripping-roll, a shaft rotated by said lever and carrying belt-shifting means whereby the several parts will act in the progressive movement of the 115 lever, substantially as specified.

60. In a starching-machine, a controlling-lever, rotating means connected thereto and extending to opposite sides of the machine, a movable cover-section provided with depending brackets, having expanded ways and rock-arms located upon said rotating means at opposite sides of the cover to travel in said ways to move, to lock closed, and to permit the removal of the cover, substantially as 125 specified.

61. In a starching-machine comprising a movable cover-section carrying a positively-driven stripping-roll, and starching mechanism, the combination with a power-shaft sup- 130

ported at one end thereof and carrying driving mechanism, a single unitary controlling lever mounted upon a shaft located at the opposite side of the machine and carrying 5 cover-operating devices, and intermediate mechanisms under the control of said lever for governing the transmission of power from said power-shaft to said stripping and starching mechanisms; substantially as specified.

In testimony whereof we affix our signatures in presence of two witnesses.
